UNITED STATES PATENT OFFICE.

JOHN C. STRNAD, OF HIGHLAND PARK, MICHIGAN, ASSIGNOR TO MAIL-OM-ETER COMPANY, OF DETROIT, MICHIGAN, A CORPORATION OF MICHIGAN.

STAMP OR LABEL AFFIXING MACHINE.

1,129,246.

Specification of Letters Patent. Patented Feb. 23, 1915.

Application filed September 11, 1911. Serial No. 648,619.

To all whom it may concern:

Be it known that I, JOHN C. STRNAD, a citizen of the United States of America, residing at Highland Park, in the county of Wayne and State of Michigan, have invented certain new and useful Improvements in Stamp or Label Affixing Machines, of which the following is a specification, reference being had therein to the accompanying drawings.

The invention relates to stamp or label affixing machines and consists in various features of construction as hereinafter set forth.

15 In the drawings,—Figure 1 is a longitudinal section partly in elevation of the machine; Fig. 2 is an end elevation thereof; Fig. 3 is a perspective view of a portion of the machine showing the strip guide detached; Fig. 4 is an elevation showing the plunger and moistener; Figs. 5 and 6 are similar views showing different steps in the operation; Fig. 7 is an elevation of the reverse side of the machine of that shown 20 in Fig. 1, illustrating the feed operating mechanism; Fig. 8 is a perspective view of the moistener detached; Fig. 9 is a cross section through the plunger and moistener; Fig. 10 is a longitudinal section through 25 the moistener and adjacent parts; Figs. 11 and 12 are perspective views respectively of the two parts forming the inclosing case; Fig. 13 is a view similar to Fig. 7 showing the parts in different positions of adjustment; Fig. 14 is an elevation of the stamp feeding pawls and holding dog; Fig. 15 is an elevation of the guide rolls between which the stamp strip is fed; and Fig. 16 is a perspective view of the strip guide.

40 It is the object of the invention to obtain a simple and compact arrangement of mechanism which is absolutely positive and certain in its operation and which prevents the extraction of the stamps or labels in any 45 other way than by the normal operation.

Generally described, the mechanism comprises a reciprocatory plunger for engaging and affixing the stamp, a strip feeding mechanism operated by said plunger during 50 its initial movement to register a single stamp therewith, a severing blade for detaching said stamp from the strip, and a moistener which is operated subsequent to the engagement of the plunger with the 55 stamp to wipe over the gummed surface of

the latter and to clear the plunger during the affixing operation.

The plunger A comprises a rod slidably engaging a bearing B on the frame C of the mechanism and provided with a head D 60 slidably engaging vertical guides E and carrying a dog F engaging a ratchet bar G or other suitable device for compelling a complete operation before reversal. The head D is provided on its under side with a suitable pad H for pressing against the stamp and with points I for perforating and holding the stamp in position during its transfer.

J is a stamp supporting bearing normally 70 in the path of the plunger, and K is a moistener preferably arranged at one end of the bearing J. The bearing J and moistener K are carried by a laterally movable member L which is operated by the plunger after 75 the stamp is pressed against said bearing so that the latter travels downward and is simultaneously withdrawn laterally until completely clear of the plunger path. This movement holds the stamp in position during the severing operation and also during 80 its subsequent movement downward, while the moistener wipes the gummed surface.

For effecting the operation just described the member L is preferably constructed to 85 slidably engage inclined bearings M and is further provided with horizontal bearings L' with which the anti-friction rolls L² on the plunger head D engage. The arrangement is such that the pressure of the rolls 90 L² on the bearings L' will force the member L to travel downward along the inclined guides M until said bearings L' are completely withdrawn from the path of the roll and the bearing J and wiper K are clear of 95 the plunger. The further movement of the plunger will cause the rolls L² to travel downward along vertical guides L³ upon the member L and hold it from returning until the plunger is withdrawn by its upward 100 movement. The member L is then automatically returned by the tension of a spring N which forces it up the inclined guides M into its initial position. The member L is preferably struck up from a sheet metal 105 blank which is bent to form parallel side flanges L⁴ at the upper ends of which the bearings L' are formed.

L⁵ are pins projecting laterally from the flanges L⁴ and which engage parallel slots 110

in the frame C constituting the inclined guides M, said slots being opened at their lower ends for engagement and disengagement of the pins. The flanges L⁴ are extended rearward to form arms L⁶ to which the spring N is detachably secured by a cross bar N' engaging notches or bearings N². Thus the construction is one which will permit the disengagement of the member L at any time for the purpose of renewing the water supply in the moistener K or for any other purpose. The moistener K is formed of suitable wick or porous pad extending into the tank K', which latter is formed beneath the bearing J for the stamp. The whole construction is one that can be easily manufactured from sheet metal blanks.

The stamp feeding mechanism comprises a suitable holder O for a roll of stamp strip, a horizontally arranged strip guide P which is in alignment with the bearing J when in its normal position, and reciprocating feeding pawls Q for engaging the perforations in the stamp strip and advancing it into registration with the plunger. It is highly desirable to provide an easy means of engaging the stamp strip with the guide, and this I have accomplished by the provision of the detachable guide P' which is slidably engageable with the main guide P. The guide P' is preferably formed of a sheet metal plate having return bent marginal flanges P² forming the edge guides for the strip. This member is insertable between the side flanges P³ of the guide P after the strip has first been engaged with the return bent flanges P², while a down bent flange P⁴ forms a finger hold for engaging and disengaging the member.

The feeding pawls Q are mounted upon a slide Q' which slidably engages a bearing in one of the flanges P³ preferably by means of pins Q² engaging guide slots P⁵ in said flange. The pawls Q are formed of resilient wire having down bent hooked ends Q³ adapted to engage with the perforations in the stamp strip.

Q⁴ is a rockable cross bar beneath the pawls Q adjacent to the hooks Q³ and which is pivotally attached at Q⁶ to the slide Q'.

Q⁶ is a pin on the bar Q⁴ engaging a cam bearing on the flange P⁸ by which in the return movement of the slide Q' said bar is rocked to simultaneously lift all of the pawls Q out of engagement with the stamp strip. This cam is preferably formed by a pivot member Q⁷ which lifts to permit the passage of the pin Q⁶ in its forward movement and which has a flange Q⁸ dropping in the path of said pin on its return movement and effecting a disengagement of the pawls as just described.

To guard against the fraudulent drawing out of the stamp strip when not operated by the feed mechanism, a reversely engag-

ing dog R is pivotally attached at R' to the slide Q'. This dog normally travels with the strip during the forward feeding thereof and during the reversal or return movement of the slide Q' is disengaged by the lifting or rocking of the bar Q⁴, which latter engages a projecting arm R² on the dog R. On the other hand when the slide Q' and pawls Q are stationary, any attempt to withdraw the stamp strip will only result in causing a sharp hooked point R³ on the dog R to cut into the strip and destroy the stamps before they can be detached.

For operating the slide Q' and feed pawls Q thereon a compound lever actuated by the plunger A is provided. This consists of the main lever S, which extends horizontally longitudinally of the frame adjacent to one side thereof, being fulcrumed at S' and having at its free end a detachable engagement with the head D. As shown, S² is a pivoted member at the free end of the lever S, which together with a projecting finger S³ on said lever forms a slotted bearing S⁴ for engaging one of the rolls L². The member S² has a downward projection, which bears against a roll S⁵ upon the frame and is held thereby from swinging on its pivot during the initial movement of the lever S. This will cause the lever to be carried down by the plunger A and head B thereon until a notch or cut-away portion S⁶ in the member S² registers with the roll S⁵. This permits the turning of the member S² on its pivot and the disengagement of the roll L² therefrom, so that in the further downward movement of the plunger the lever S remains stationary. T is a second lever pivotally attached at T' to the frame and having a laterally extending portion which is connected by a pin T² engaging a slot T³ with the lever S. Beyond the point of engagement between these levers the lever T extends downward, and is coupled to the slide Q' by a pin T⁴ engaging a slotted bearing T⁵. Thus, the vertical swinging movement of the lever S is translated into a substantially horizontal swinging movement of the lever T, which actuates the slide Q' in the manner already described.

The mechanism thus far described is housed in a suitable casing, preferably comprising the members U V. These are secured together by an interlocking engagement of the slotted bearings U' with headed pins V' and a key-actuated lock W' which holds all of the parts from disengagement. The member V' is preferably provided with a transparent panel V² through which the operation of the mechanism within the case can be observed from without. A suitable counter at X is also preferably arranged within the case and is operated by any suitable connection with the mechanism (not shown in detail).

With the construction as described, in operation, the roll of stamp strips is first placed in position by detaching the housing and placing the roll in the cylindrical holder O. From this holder the end of the strip is drawn out between guide rolls O' O² and is engaged with the guide P' which is first detached from the stationary guide P. The insertion of the strip through the guide P' is readily accomplished when the latter is detached, and after threading, the member P' is reengaged with the stationary guide P. To prevent tearing of the strip during the engagement of the guide by contact with the pawls Q the bar Q⁴ is lifted by means of a hook Q⁸, so as to raise all of the pawls Q and also to lift the holding dog R. This will clear the path of the guide P' and strip therein during engagement with the stationary guide P. When the stamp strip is in position the case is again replaced and the machine is in condition for operation. Each time the plunger A is depressed the following operation will be performed: During the initial downward movement of the plunger the roll L²—which is in engagement with the lever S—will cause the rocking of said lever, which is communicated through the compound lever T to the slide Q'. This will cause the forward movement of said slide and the pawls Q thereon, which latter engage the perforations in the stamp strip and carry it forward, feeding the free end above the bearing J and beneath the descending head D of the plunger. At the completion of the movement imparted to the slide Q' the stamp strip is advanced sufficiently to bring one stamp in registration with the pad H on the plunger head D, while the line of perforations between this stamp and the next adjacent stamp is in exact registration with a cut-off or shearing blade X' upon the head D. This blade is adapted to travel across the end of the stationary guide P, forming the coöperating shearing member, and to lessen the resistance in shearing the guide P is preferably inclined upward along its shearing edge from the sides to the center, as indicated at X². Thus, when the shearing blade X first engages the stamp strip the contact will be at the center of the inclined member X², cutting this portion first and progressively cutting toward the edges of the strip.

Before the blade X' begins the shearing cut, the pad H on the head D comes into proximity to the projecting stem, which is above the bearing J, and the points I will engage and deliver the stamp so as to hold it from displacement after severing. The shearing action does not take place until the pivoted member S² on the lever S registers its cut-away portion S⁶ with the roll S⁵, which permits the disengagement of the roll L² from the lever and prevents any further

movement of the stamp strip, as shown in Fig. 13. The head D however continues its downward movement, and as soon as pressure of the pad H is brought to bear upon the severed stamp on the bearing J the rolls L² will engage with the horizontal bearings L' on the member L, forcing downward this member along the inclined guides M, and against the tension of the spring N until the bearing J and moistener pad K are completely withdrawn from beneath the stamp. The gummed surface of the latter is moistened by contact with the pad K during the lateral movement thereof, and consequently the further depression of the plunger which carries said stem in contact with the envelop or other surface to which it is to be affixed will complete the affixing operation. The plunger will then be returned by the tension of a suitable spring, permitting the member L and slide Q' to assume their respective initial positions. During this movement the pin Q⁶ on the rockable bar Q⁴ will pass up the incline of the flange Q⁸ upon the member Q', which will lift said bar Q⁴ together with the pawls Q and dog R so as to completely disengage the same from the stamp strip.

Whenever it is necessary to renew the water supply in the moistener, the case is removed and the bar N' is disengaged from the bearings N², relieving the tension of the spring N and permitting the slipping out of the member L from the inclined guides M. The tank K' may then be re-filled by detachment of a stopper K² and the member L quickly replaced in position.

When the stamp strip is drawn off from the roll in the case O, it will be permanently curled to such an extent as to render feeding along the guide difficult. This I have corrected by forming the guide rolls O' and O² between which the stamp strip is withdrawn, respectively concave and convex. Thus the strip in passing therebetween will be bent into a curved cross section which will neutralize the tendency to curl. The same effect is produced at the end of the guide P when the strip is drawn over the portion X' as this will bend the strip so as to prevent curling of the projected stamp before the latter is severed.

What I claim as my invention is,—

1. In a label-affixing machine, the combination with an affixing plunger, of a moistening member arranged in the path of said plunger, means for feeding the label strip between said plunger and member, and means for withdrawing said member laterally from beneath the label directly actuated by said plunger.

2. In a label-affixing machine, the combination with an affixing plunger, of a guide for the label strip extending transversely of the path of movement of said plunger at one side thereof, a moistening member aligned with

1 said guide in the path of said plunger, means actuated by said plunger for feeding the label strip along said guide and between said plunger and moistening member, and means 5 actuated by the depression of said plunger beyond the point of engagement with the label for withdrawing said member laterally to clear the plunger.

2 3. In a label-affixing machine, the combination with an affixing reciprocatory plunger, of a moistening member arranged across the path of said plunger, means for feeding the label between the plunger and said member, and parallel guides for said member 10 arranged at an angle to the path of movement of said plunger, whereby the pressure of said plunger upon said member will cause the lateral withdrawal thereof.

4 4. In a label-affixing machine, the combination with an affixing reciprocatory plunger, of a movable moistening member arranged across the path of said plunger, and a guide for said movable member arranged at an angle to the path of movement of said 15 plunger, whereby said movable member is directly actuated by said plunger to be withdrawn laterally from the path thereof.

5 5. In a label-affixing machine, the combination with an affixing reciprocatory plunger, of a movable moistening member arranged across the path of said plunger and actuated thereby, and parallel guides for said movable member extending at an angle to the path of movement of said plunger and 20 causing the lateral withdrawal of said member.

6 6. In a label-affixing machine, the combination with an affixing reciprocatory plunger, of a moistening member extending across the path of said plunger and actuated thereby, and guides for holding said member parallel to the face of said plunger and extending at an angle to the direction of movement thereof, whereby the pressure of said 25 plunger will cause the lateral withdrawal of said member.

7 7. In a label-affixing machine, the combination with an affixing reciprocatory plunger, of a moistening member arranged across the path of said plunger and actuated thereby, guides for said member arranged at an angle to the path of movement of said plunger whereby the depression of the latter will cause the lateral withdrawal of the former, 30 and resilient means operating on said member to return the same upon the withdrawal of said plunger.

8 8. In a label-affixing machine, the combination with an affixing reciprocatory plunger, of a moistening member arranged across the path of said plunger, a guide for said member extending at an angle to the path of movement of said plunger, laterally slideable coöperating bearings on said plunger 35 and member for causing the lateral with-

drawal of said member upon the depression of said plunger, resilient means for returning said member, and a bearing for holding said member from return during the continued movement of said plunger.

9 9. In a label-affixing machine, the combination with an affixing reciprocatory plunger and a guide member therefor, of a moistening member extending across the path of said plunger, a guide for said member inclined to the guide for said plunger, coöperating bearings on said plunger and member having a laterally movable engagement, and a bearing coöperating with one of said bearings having a longitudinal traveling engagement therewith, whereby said member is laterally withdrawn from the path of said plunger and held in its withdrawn position during the continued movement of said plunger.

10 10. In a label-affixing machine, the combination with an affixing reciprocatory plunger, of a movable member extending across the path of said plunger, a guide for said movable member at an angle to the direction of movement of said plunger whereby the direct actuation of the latter will cause the lateral withdrawal of the former, means for feeding a gummed label between said plunger and member, and a moistener carried by 90 said member actuated thereby to wipe across the gummed surface of said label during the lateral withdrawal of said member.

11 11. In a label-affixing machine, the combination with an affixing reciprocatory plunger, of a guide for the label strip extending transversely to the direction of movement of said plunger, a member in alinement with said guide and in the path of said plunger, a guide for said member inclined to the direction of movement of said plunger, means actuated by said plunger for advancing the label strip along said guide and above said member, a cut-off for severing the label advanced beneath said plunger from the strip, 100 and a moistener carried by said member and actuated thereby to wipe across the gummed surface of said label.

12 12. In a label-affixing machine, the combination with an affixing reciprocatory plunger, of a frame in which said plunger is mounted, guide bearings in said frame at an angle to the direction of movement of said plunger, and a moistening member detachably engaging said angling guide bearings 115 normally in the path of the plunger and directly actuated thereby to be laterally withdrawn from said path upon the depression of said plunger.

13 13. In a label-affixing machine, the combination with an affixing reciprocatory plunger, of a frame in which said plunger is mounted, a guide on said frame at an angle to the direction of movement of said plunger, a member detachably engaging said 125

- guide directly actuated by said plunger, means for feeding a label between said plunger and member, and a moistener carried by said member and actuated thereby to wipe 5 across the gummed face of said label.
14. In a label-affixing machine, the combination with an affixing reciprocatory plunger, of a frame in which said plunger is mounted having parallel side plates, slotted 10 guides in said side plates arranged at an angle to the direction of movement of said plunger, a member detachably engaging said slotted guides and normally in the path of said plunger, and a moistener carried by 15 said detachable member.
15. In a label-affixing machine, the combination with an affixing reciprocatory plunger, of a frame in which said plunger is mounted having parallel side plates and 20 slotted guides on said side plates at an angle to the direction of movement of said plunger, a member fitting between said plates detachably engaging said angling guides, a moistener carried by said member, and 25 means for yieldably holding said member normally in the path of said plunger whereby the direct actuation of said plunger will cause the lateral withdrawal of said member and moistener.
16. In a label-affixing machine, the combination with an affixing reciprocatory plunger, of a guide for the label strip extending transverse to the direction of movement of 30 said plunger, a shearing blade carried by said plunger and co-acting with the end of said guide, a member arranged in the path of said plunger and normally in substantial alignment with said guide, a guide for said member inclined to the direction of movement of said plunger, means actuated by 35 said plunger for advancing the label strip along said guide and for projecting one label in registration with said plunger and mem- 40
- ber, and a moistener carried by said member adapted to wipe across the gummed face 45 of said label after the shearing of the same from the strip and during the further depression of said plunger.
17. In a label-affixing machine, the combination with an affixing reciprocatory plunger, of a frame in which said plunger is mounted having parallel side plates and inclined parallel guide slots in said side plates, a moistening member fitting between said side plates detachably engaging said parallel 50 guide slots, a roll on said plunger, and a laterally extending bearing on said member in the path of said roll whereby the depression of said plunger will cause the lateral withdrawal of said member, and a spring 55 detachably engaging said member for yieldably holding the same in normal position.
18. The combination with an affixing plunger, of a strip guide extending transversely thereof, a moistening member in substantial alignment with said strip guide and normally in the path of said plunger being 60 compressible by the latter, and means co-operating with said member for withdrawing the same laterally during the further depression of said plunger. 65
19. The combination with an affixing plunger, of a moistening member normally in the path of said plunger and compressible 70 by the latter, means actuated during the initial movement of said plunger for feeding a strip between the plunger and said member, and means for laterally withdrawing said member during the downward movement thereof with said plunger. 75

In testimony whereof I affix my signature in presence of two witnesses.

JOHN C. STRNAD.
